UNITED STATES PATENT OFFICE

163,721

CHARM OR THE LIKE

Robert Vandergeenst, Le Mans, France

Application November 2, 1950, Serial No. 12,815

Term of patent 7 years

(Cl. D45—17)

To all whom it may concern:

Be it known that I, Robert Vandergeenst, a citizen of France, residing at Le Mans (Sarthe), France, have invented a new, original, and ornamental Design for Charm or the Like, of which the following is a specification, reference being had to the accompanying drawing, forming a part hereof.

The figure is a front elevation of a substantially flat charm embodying my new design, the back of the rotatable disk element being substantially the same in appearance as the front thereof and the back of the stationary element being substantially plain.

I claim:

The ornamental design for a charm or the like, as shown and described.

ROBERT VANDERGEENST.
